[57] **ABSTRACT**

A pusher furnace for heating workpieces having an ejecting apparatus which grips each workpiece emerging from the furnace exit, vibrates the workpiece to prevent fusing of the workpiece with the one immediately behind it and withdraws the workpiece at the appropriate time.

WORKPIECE GRIPPER HAVING VIBRATING MEANS THEREON

The invention relates to a pusher furnace for heating workpieces, such as small ingots, to their hot forming temperature, the preheated workpieces being ejected out of the furnace exit at predetermined intervals.

For the mass production of forgings it is a well established practice to heat the small ingots that are to be delivered to a forging machine to their hot forming temperature in a pusher furnace which may be gas, oil or inductively heated. In the case of steel this temperature is usually between 1200° and 1280° C. For the purpose of conveying the small ingots through the furnace a lifting beam system may be useful, although the mechanical complexities of such a system involve a considerable expenditure. Mechanically much simpler than a lifting beam type of furnace is a pusher furnace in which a column of consecutive ingots is conveyed intermittently through the furnace to the exit end by a pusher which at each forward step advances the column by the length of one ingot. However, the advantage afforded by the greater simplicity of this arrangement is offset by the drawback that the forces acting between the ingots during the feed steps tend to cause the contacting faces of consecutive ingots in the high temperature zone of the furnace to fuse and weld together. Attempts to separate ingots that have thus fused together by providing a breaker device at the furnace exit have not given satisfactory results since, particularly at final temperatures exceeding 1,250° C, the fused steel ingots are extremely firmly stuck together when they leave the furnace exit. To enable ingots to be reliably separated very powerful bending or percussion devices would be needed and, preferably these would have to work automatically. Such equipment cannot in practice be produced at a reasonable cost.

It is the object of the present invention to provide a pusher furnace, particularly an inductively heated pusher furnace which ejects the workpieces, particularly small steel ingots that have been heated inside the furnace, consecutively at predetermined intervals, and which prevents the workpieces from sticking or welding together, the fully heated workpiece being pulled from the furnace exit. According to the invention this is achieved by the provision of ejector means at the furnace exit comprising ejecting elements which are mounted in a holder and adapted to grip the flanks of the workpiece and to move it forwards, the holder being supported so that it can move in a direction normal to the direction of advance of the work, and a vibrator being coupled thereto.

During operation the described ejector elements apply vibratory motion to the fully preheated workpiece waiting at the furnace exit and they thereby prevent its trailing end in the high temperature zone of the furnace from being welded to the abutting leading end of the next following workpiece.

In order to permit the ejector elements to perform such vibratory movements their holder is preferably mounted with the interposition of elastic elements.

In an alternative preferred embodiment of the invention, the holder is supported in a manner permitting rotation of the elements about an axis parallel to the direction of workpiece advance. A rotary vibratory motion can thus be imparted to the holder and its ejector elements.

According to another feature of the invention, the ejector elements may be constituted by clamping members and the holder may incorporate means for opening and closing the clamping members. In such an arrangement the holder together with the vibrator may with advantage be mounted in a carriage or slide which is movable in the direction of workpiece advance so that by moving the slide the workpiece gripped by the clamping members can be withdrawn from the furnace exit.

In yet another preferred embodiment of the invention the ejector elements for withdrawing the workpieces in advancing direction are constituted by driven bodies adapted to roll on the workpiece surface, particularly in the form of rollers, cylinders or endless traveling chains.

The invention will be hereinafter described in greater detail, reference being made to the drawings in which:

FIG. 1 shows the exit of an inductively heated pusher furnace for heating small steel ingots and shows associated ejector equipment adjacent the furnace exit.

FIG. 2 shows the ejector equipment in a section taken on the line A - B in FIG. 1.

FIG. 3 shows a modified holder for the clamping elements.

FIG. 4 shows a further embodiment of the ejector.

Referring to FIG. 1, the pusher furnace is equipped with a liquid-cooled induction coil 1 and contains slide rails 2 for supporting small steel ingots 3 that are to be heated. Adjacent the furnace exit is an ejector device comprising tong-like clamping members 4 mounted on a holder 5 which contains means (not shown) for controllably opening and closing clamping members 4. The holder 5 is mounted on a slide 8 with the interposition of spring elements 6 which permit a vibratory motion normal to the direction of advance through the pusher furnace to be imparted to the holder by a vibrator 7 in the manner indicated by arrows 9.

The slide 8 itself together with its clamping members 4, its holder 5 and the vibrator 7 are slidably movable on bars 10 in relation to the furnace in the direction in which the workpieces advance.

Let it be assumed that after the completion of the ejection of one ingot the next fully heated ingot at the head of a column of ingots occupies a position in the furnace exit as illustrated in FIG. 1.

The leading end of this fully heated block 3 then projects slightly from the furnace exit, whereas its tail end 11 is abutted by the second block still in the high temperature zone of the furnace. Slide 8 of the ejector equipment is now advanced towards the furnace exit into the position in FIG. 1, the clamping members are closed and grip the ingot 3' that is to be ejected. The vibrator is started and imparts to the ingot 3' a vibratory motion in a direction normal to the direction in which the block advances. The relative motion thus produced between the ingot that is to be ejected and the next ingot in the column prevents these two ingots from sticking or fusing together and any incipient fusion or weld at their point of contact will be nullified.

Simultaneously with the next advancing step of the column of ingots in the furnace the fully heated leading ingot 3' is now withdrawn from the furnace exit at the same or at a higher speed by withdrawal of the slide 8 in the direction of the arrow 12 and then deposited on

a transferring means 19 when the clamping members 4 open. The transferring means carries the ingot to the forging machine. The withdrawal of the small ingot 3' may with advantage already begin before the next ingot is advanced by the next step of the pusher.

FIG. 3 is a modified holder for the clamping members. This is attached without the interposition of spring elements to the slide or carriage of the ejector equipment, the slide or carriage being movable in the direction in which the workpieces travel through the furnace. The holder 5' which serves for supporting the clamping members 4' and their actuating means in this embodiment has a cylindrical external surface and is rotatably mounted in a frame-like slide 8' fitted with rollers 13. The frame structure itself is bodily slidably movable along bars 10' extending in the direction of advance of the ingots. By means of a vibrator 7' a rotary oscillation can be applied to the holder 5', the clamping members 4' and to the ingot which they have gripped. This oscillation has an analogous effect to that achieved in the previously described embodiment shown in FIGS. 1 and 2. The present modification has the additional advantage that the small ingot 3' which has been separated from the following column of ingots and withdrawn from the furnace exit can be deposited for instance in a chute 20 and thus removed after it has been released by the clamping members 4'.

This latter advantage is also achieved in a further embodiment of the ejector shown in FIG. 4. This can be used with particular advantage when the length of the ingots is considerable in relation to their diameter. Contrary to the previously described embodiments of the ejector equipment in the arrangement of FIG. 4, the ejector elements include conical rollers 14 which are rotatably mounted on a shaft 15 that can be driven and that extends across the direction of advance of the ingots. The holder 5'' is associated with a vibrator 7'' and supported from a pedestal 17 in the furnace frame with the interposition of spring elements 6'.

In this embodiment the column of ingots is advanced in the furnace at each feeding step so that the leading ingot which is fully heated and ready to be ejected can be engaged by the ejector rollers 14. Vibratory motion in the direction of the arrows 18 is imparted to this ingot by the vibrator 7'' acting through the holder 5'', the shaft 15 and the conical ejector rollers 14. This vibration prevents the ingots that are about to be ejected from sticking or welding to the next following ingot inside the furnace or at least it causes any incipient fusion or weld to be rebroken. Owing to the high frictional resistance between the hot ingots 3' and the ejector rollers 14, rotation of the rollers which now begins causes the ingot that is to be ejected to be pulled out of the furnace exit, to be deposited for instance on a chute 20 leading to an associated forging machine. If the available friction of the pair of rollers should not be sufficient, then several synchronously driven roller pairs may be provided in tandem in the direction of advance of the work.

According to a further modification of FIG. 4, not exemplified in the drawings, a second pair of rollers may be mounted above the described roller pair on a vertically movable horizontal shaft. Each feeding step advances the next ingot that is to be ejected between the two roller pairs. The upper roller pair is then lowered on the ingot and both pairs grip the ingot that is to be

ejected like clamping members.

Many changes and modifications in the above described embodiments of the invention can be made without departing from the scope of the invention. Accordingly, that scope is intended to be limited only by the scope of the appended claims.

What is claimed is:

1. In a pusher furnace for inductively heating workpieces to their hot forming temperature before they are ejected at predetermined intervals at the furnace exit, the improvement comprising means for ejecting the fully heated workpieces at the furnace exit including ejecting elements mounted on a holder and adapted to grip the flanks of the workpiece and to withdraw the same in the direction of workpiece advance, said holder being supported so that it can move in a direction normal to the direction of workpiece advance, and a vibrator being coupled to said holder said vibrator preventing fusing of the gripped workpiece with one immediately therebehind.
2. In a pusher furnace according to claim 1, the further improvement comprising elastic means mounting said holder.
3. In a pusher furnace according to claim 1, the further improvement comprising means for mounting said holder rotatably about an axis parallel to the direction of workpiece advance.
4. In a pusher furnace according to claim 1, the improvement wherein the ejecting elements include clamping members and the holder includes means for opening and closing the clamping members.
5. In a pusher furnace according to claim 4, the improvement wherein said holder together with the vibrator is mounted in a carriage which is movable in the direction of workpiece advance.
6. In a pusher furnace according to claim 1, the improvement comprising means for propelling the workpieces in the direction of workpiece advance including driven bodies for rolling on the workpiece surface.
7. In a pusher furnace according to claim 6, the improvement wherein said ejecting elements include driven rollers.
8. Apparatus for ejecting hot workpieces from a pusher furnace comprising:
  - means for gripping a workpiece at the exit of said furnace,
  - means for moving said gripping means to withdraw the gripped workpiece from said furnace, and
  - means coupled to said gripping means for vibrating said gripping means and the gripped workpiece
 said means for vibrating preventing fusing of the gripped workpiece with one immediately therebehind.
9. Apparatus as in claim 8 wherein said gripping means includes tong-like, clamping members, a movable carriage, means mounting said clamping members, elastic means connecting said carriage to said clamping members mounting means, and means connecting said vibrating means to said clamping members mounting means.
10. Apparatus as in claim 8 wherein said gripping means includes clamping members, means for mounting said clamping members for rotatory vibratory motion, and means for connecting said clamping members mounting means to said vibrating means.
